UNITED STATES PATENT OFFICE.

ADELBERT T. MUTH, OF LA CROSSE, WISCONSIN.

DESIGN FOR A SIGN-HOLDER.

SPECIFICATION forming part of Design No. 32,692, dated May 22, 1900.

Application filed March 29, 1900. Serial No. 10,709. Term of patent 14 years.

To all whom it may concern:

Be it known that I, ADELBERT T. MUTH, a citizen of the United States, residing at La Crosse, in the county of La Crosse and State 5 of Wisconsin, have produced a new and original Design for a Sign-Holder, of which the following is a specification.

This invention relates to a new and original design for a sign-holder, and the essential 10 feature resides in an upper circular looped terminal supported by a twisted stem having an open circular base.

The accompanying drawing represents a 15 perspective view of a sign-holder embodying the features of the design.

The numeral 1 designates a twisted stem which is vertically disposed and has at its upper extremity two circular loops 2, which are closely arranged, and at its lower ex-

tremity the said stem continues into an open 20 circular holding-base 3, formed by bending the terminals of the wires from the stem into approximate semicircular form and to one side of the vertical plane of the said stem.

The twist of the stem is regular, and all the 25 members are sufficiently rigid to maintain their shape.

Having thus described the invention, what is claimed as new is—

The design for a sign-holder, herein shown 30 and described.

In testimony that I claim the foregoing as my own I have hereto affixed my signature in the presence of two witnesses.

ADELBERT T. MUTH.

Witnesses:

W. J. HICKISCH,
GEO. J. FRIES.
